UNITED STATES PATENT OFFICE.

CHARLES E. MARTIN, OF MANSFIELD, OHIO.

SILO-ROOF.

1,172,721.

Specification of Letters Patent. Patented Feb. 22, 1916.

Application filed December 18, 1914. Serial No. 877,991.

To all whom it may concern:

Be it known that I, CHARLES E. MARTIN, a citizen of the United States of America, residing at Mansfield, in the county of Richland and State of Ohio, have invented certain new and useful Improvements in Silo-Roofs, of which the following is a specification.

This invention relates to certain new and useful improvements in silo roofs and the primary object of the invention is to provide a roof which permits the space between the top of the silo and the roof to be utilized for storage purposes.

It is well known that in ordinary silo structures, the space between the top of the silo and the roof cannot be utilized for storage because such space is inaccessible and no provision is made whereby same can be filled, thus resulting in reduction of the silo capacity.

It is further well known that the contents of the silo sink more or less, especially if the silage has not been tightly packed, therefore by providing means to permit easy and convenient access to the normally unfilled top of the silo, the silage may be packed tightly, and the space completely filled, thus materially increasing the capacity of the silo.

In brief the invention resides in the formation of an opening in the top part of the roof, and in the provision of a hood to cover the opening, with means to support the hood in different open positions.

Further and other objects will be later herein set forth, and manifested in the course of the following description.

In the drawings: Figure 1 is a perspective view of the roof showing the hood in open position; Fig. 2 is a central vertical sectional view of Fig. 1; Fig. 3 is a fragmentary elevation of the hinged cover in open position taken on the line 3—3 of Fig. 1; and Fig. 4 is a section taken on the line 4—4 of Fig. 3.

The silo is designated 1 in the drawings and has a roof 2 preferably of frusto-conical formation, the roof being composed of a series of tapered corrugated sections attached at their lower ends by means of clips 3 to the silo body and having their upper ends resting against an angle-iron ring 4 and secured to the latter by means of flexible straps 5 which are wrapped around the ring.

Angle-iron legs 6, 7, and 8, are utilized as a means of support for the ring 4 and the roof structure as a whole, these legs having a tripod-like relationship and being connected at their upper ends to the ring and at their lower ends to the silo body, as depicted in Fig. 2 of the drawings.

The ring 4, it will be evident, bounds or defines the opening which provides an inlet to the silo roof, which inlet is closed by a hood 10 that is constructed as follows: An outer angle-iron ring 11 is provided and connected to an inner anchorage ring 12 in spaced relation thereto by means of spacing sleeves 13 and bolts 14. A series of corrugated tapered sections comprise the hood proper 10 and are provided with flexible ties 15 which latter are hooked or bent to engage beneath the anchorage ring 12, as depicted in Fig. 4 of the drawings. The sections of the hood are secured at their upper ends to a ventilator 16. For the purpose of bracing the hood and strengthening the same, a series of braces 17, 18, and 19, are employed, which braces have a triangular relationship and are secured to the ring 11. Hinges 20 are employed to hingedly connect the hood to the ring 4.

In order to adjustably support the hood in varying open positions, a pair of bars or rods 21 and 22', are provided, the bars being pivotally attached at their upper ends to brackets 22 and 23 which latter are secured to the brace 17, the latter thus serving not only as a brace, but as a means of connecting the bars or rods 21 and 22' to the hood.

The legs 6 and 8 which act to support the ring 4 and to brace and strengthen the roof 2 also perform the function of adjustably supporting the lower ends of the bars or rods 21 and 22' for which purpose the legs 6 and 8 are provided with a series of apertures 25 which receive pins 24 that are removably connected to the lower ends of the bars or rods 21 and 22'.

When the hood is in closed position, rings 11 and 12 excepting the horizontal web of 11 engage or are received within the ring 4, while the horizontal web of the ring 11 extends over the ring 4 and engages the horizontal web of the latter, thus acting to restrict the extent of downward movement of the hood.

From the above it will be apparent, that an inlet to the silo is provided at the very

highest point thereof, thus allowing the silo to be packed to its complete limit of holding capacity, and also to allow the silage to be tamped or rammed so as to receive further 5 silage and thus completely fill the silo.

It will also be observed that the rings 11 and 4 make a weatherproof joint and that the hood structure is amply and fully braced. In addition the pair of rods 21 and 10 22' serve, by virtue of engaging the hood at points adjacent its periphery, to effectively 15 secure the hood in raised position, and also enable the hood to be easily raised or lowered by grasping one rod in each hand, 15 since the rods are located equidistantly on opposite sides of the hinge 20.

What is claimed is:

1. In a silo, a roof of frusto-conical form, a hood composed of an inner anchorage ring, 20 an outer angle-iron ring spaced from the anchorage ring, and secured thereto, a ventilator above said rings, roofing sections secured to the ventilator and engaged with the outer ring, ties connected to the sections 25 and with the anchorage ring and being engaged in part in the space between said rings, and means to hingedly connect the outer ring to the silo body.

2. In a silo, a cylindrical body, a frusto- 30 conical roof, a ring at the top part of the roof, a hood hinged to the ring, a ring carried by the hood and adapted to be received within the ring secured to the roof, braces for the roof, and rods hinged to the hood at 35 one end and adjustably connected to the braces at their opposite ends.

3. In a silo, a roof of frusto-conical form, an angle-iron ring bounding the edge of the opening at the roof top, and a hood hinged

to the ring carrying a ring that is adapted 40 to fit within the angular iron ring of the roof.

4. In a silo, a frusto-conical roof, a hood hinged to the roof, said hood being composed of inner and outer rings and sections 45 secured to the inner ring, braces for the rings, a pair of brackets borne by one of the braces, rods pivoted to one of the brackets, and means to secure the rods in adjusted position to the roof.

5. In a silo, a body having a roof the latter provided with a top opening, and a hood for the opening including inner and outer spaced concentric rings, means to rigidly 50 connect the rings, roofing sections seated on the outer ring, and means between the sections and rings for securing the sections to the latter, said securing means extending in 55 part in the space between the rings.

6. In a silo, a body, a roof on the body 60 formed with a top opening, a hood for said opening including an outer angle iron ring and an inner ring connected thereto in spaced relation, braces seated on top of the horizontal web of the angle iron ring and 65 secured to said web, roofing sections seated on the said web, means to secure the sections to the inner ring disposed in part in the space between the rings, and means to hingedly connect the angle iron ring to the 70 roof.

In testimony whereof I affix my signature in presence of two witnesses.

CHARLES E. MARTIN.
